United States Patent Office

Des. 193,231
Patented July 10, 1962

193,231

PUNCH

Peter M. Klein, Ogdensburg, N.Y., assignor to Natser Corporation, Ogdensburg, N.Y., a corporation of Nevada

Filed Dec. 15, 1961, Ser. No. 67,925

Term of patent 14 years

(Cl. D74—1)

FIG. 3.

FIG. 5.

FIG. 4.

FIG. 1 is a perspective view of a punch embodying my new design.

FIG. 2 is an elevational view of one of the two like sides thereof the broken line illustration of the gauge having been eliminated from this figure and the subsequent figures for convenience of illustration.

FIG. 3 is a front elevational view thereof.

FIG. 4 is a back elevational view thereof.

FIG. 5 is a top plan view thereof.

The dominant features of the design are shown in full lines.

I claim:

The ornamental design for a punch, substantially as shown and described.
